US00D990469S

(12) **United States Design Patent** (10) Patent No.: **US D990,469 S**
Dong et al. (45) Date of Patent: ** Jun. 27, 2023

(54) **SMART WATCH**

(71) Applicant: **OnePlus Technology (Shenzhen) Co., Ltd.**, Guangdong (CN)

(72) Inventors: **Ruiping Dong**, Shenzhen (CN); **Haoran Liu**, Shenzhen (CN); **Xinyi Jiang**, Shenzhen (CN)

(73) Assignee: **ONEPLUS TECHNOLOGY (SHENZHEN) CO., LTD.**, Guangdong (CN)

(**) Term: **15 Years**

(21) Appl. No.: **29/767,004**

(22) Filed: **Jan. 20, 2021**

(30) **Foreign Application Priority Data**

Sep. 11, 2020 (CN) 202030539988.5

(51) LOC (14) Cl. **14-02**
